UNITED STATES PATENT OFFICE.

WILFRED H. KUHN, OF DETROIT, MICHIGAN.

STEAM TRAP.

Application filed June 29, 1925. Serial No. 40,243.

This invention relates to a device for removing water of condensation from a steam line. An object of the present invention is to provide an efficient device of compact 5 form and arrangement whereby space is conserved and a construction provided which may be installed in places where devices of this character, as usually constructed, could not readily be used. A further object is to 10 automatically remove entrained air in the steam line along with the water of condensation and to provide an arrangement embodying a removable head or cover which forms a support for the valve operating 15 mechanism, whereby ready access to the mechanism is had through the removal of the head. It is also an object to provide certain other new and useful features in the construction and arrangement of parts, all 20 as hereinafter set forth, and more particularly pointed out in the appended claims.

With the above and other ends in view, the invention consists in providing an arrangement whereby the bucket or float and valve 25 operating mechanism actuated thereby are carried by a detachable head, and further consists in the arrangement of the bucket and operating mechanism, and also in the matters of the construction and arrangement 30 of the parts, all as hereinafter set forth and more particularly pointed out in the appended claims, reference being had to the accompanying drawing in which:

Figure 1 is a transverse vertical section through a device illustrative of the present 35 invention;

Figure 2 is a horizontal section through the lower end of the bucket, substantially upon the line II—II, of Figure 1, and

Figure 3 is a horizontal section upon the 40 line III—III of Figure 1.

In the drawing, 1 indicates a suitable casing, which is preferably of cylindrical form and is provided with an opening 2 near its lower end through which sediment accumulating 45 in the bottom of the casing may be drawn off, said casing being also formed with a horizontal outstanding flange 3 at its upper end for the attachment thereto of a head 4. This head is provided with an inlet 50 passage 5 at one side and an outlet 6 at the opposite side, the inlet being screw threaded to receive the steam pipe of the line from which it is desired to draw the water of condensation, and the outlet being also screw 55 threaded to receive a pipe for carrying away

the water. The outlet 6 is in direct communication with a chamber 7 formed in the head 4 and separated from the water chamber 8 of the casing 1 by a dividing wall 9. 60 The inlet passage 5 opens through this wall 9 and depending from the wall is a flange 10 forming a baffle to direct the incoming steam and water downwardly within the chamber 8. The wall 9 is also formed with 65 an upwardly extending cylindrical portion 11 at the axis of the head and an opening 12 in the wall is closed by a depending tubular member 13 which is secured at its upper end to the lower side of the wall with the passage 70 formed thereby, in line with the opening 12. The lower end of the tubular member 13 is enlarged as at 14 to provide a chamber 15 within which suitable lever mechanism is 75 pivotally supported, the lower side of the chamber 15 being open.

A bucket or float 16, which is of the usual cup shape and open at its upper end, is positioned within the chamber 8 and surrounds the tubular member 13 and its enlarged 80 lower end. This bucket has a free vertical movement within the chamber 8 and is designed to float within the water of condensation until such time as the water rises within the chamber 8 and overflows into the bucket 85 to weight the bucket and cause a downward movement thereof. This bucket is guided in its up and down movement by means of a guide rod 17, which is secured at its lower end to the closed bottom of the bucket and 90 extends upward through an opening 18 in the upper wall of the enlarged lower end 14 of the member 13. This member 13 also has a laterally extending arm 19 near its upper end, which arm is provided with an opening 95 through which the rod 17 extends. The rod, therefore, is free to move up and down with the bucket and forms a guide therefor.

The head 4 is provided with a dome-shaped cap 20 detachably secured to the head 100 over an axial opening therein and the cylindrical upward extension 11 on the head is internally screw threaded to receive a valve cage 21, which cage is screw threaded at its upper end to receive a cap nut 22. A disk 105 23, having an axial opening 24, is detachably held to its seat upon the upper end of the cage 21 by means of the cap nut 22, so that this disk which forms the seat for a valve, may be readily removed and reversed in its 110 position, if so desired, to provide a new seat for the valve. Seating upwardly against

this seat is a valve 25, which consists of a cylindrical body tapered at both ends and detachably secured within a guide member 26 by means of a pin 27. The guide member 5 is formed with wings 28 to fit within the valve cage 21 and slide freely therein, the wings forming a guide for the valve to direct it into engagement with the opening 24 in the disk 23. Within the lower end of the 10 bore of the guide member 26 in which the valve 25 is secured, is a head 29 upon the upper end of a valve rod or stem 30, which extends downwardly within the tubular member 13 and is pivotally attached at 31 15 to a lever 32 located within the chamber 15 of the enlarged lower end 14 of the member 13. As shown in Figures 1 and 2, a collar 30^a is attached to the valve rod 30 above the lever 32 while the lower threaded end of the 20 valve rod below the lever receives the nut 30^b. When the bucket 16 is disengaged from the guide rod 17, access is had to the lever mechanism to permit the separation of the lever 32 and valve rod 30 whereby the latter may 25 be freely moved upwardly through the valve cage for disassembly. This lever 32 is pivotally supported, as at 33, upon an end wall of the chamber 15, and at its opposite end is provided with an elongated opening or 30 slot 34, to receive a pin 35 carried by the guide rod 17.

Steam and water of condensation, entering through the inlet 5, passes into the chamber 8 of the casing 1, and as the water accumulates in this chamber, the bucket 16 floats therein and is thereby raised to the upper limit of its movement, thus turning the lever 32 upon its support 33 and raising the valve rod 30 and its connected guide member 26 and valve 25, thus holding the valve seated while the bucket is buoyant. Further accumulation of water in the chamber 8 causes its level to rise until it reaches the upper end of the bucket, when it will 45 overflow into the bucket. This overflow of water into the bucket decreases its buoyancy and causes it to finally descend rapidly within the body of water in the chamber 8. This downward movement of the bucket operates the lever 32, valve rod 30, and its connected valve 25, and moves the valve away from its seat, opening the outlet 24 in the seat.

Steam entering through the inlet 5 maintains a pressure within the chamber 8 upon 50 the body of water therein and, therefore, as soon as the outlet opening 24 in the valve seat is opened by the fall of the bucket and the movement of the valve, this steam pressure will force the water contained in the bucket up through the passage formed by the tubular guide and supporting member 13 and past the wings of the guide member 26, and out through the opening 24, where it escapes into the chamber formed by the 55 cap 20 and falls into the chamber formed in

the head, from which it passes out through the outlet 6.

As the water is thus forced out of the bucket, the bucket will again rise and close the valve, the water being forced by the 70 steam pressure from the bucket through the open lower end of the chamber 15 and integral tubular member 13, which provides an outlet passage for the water. However, when the water level in the bucket falls to a 75 plane below the upper wall of the enlargement 14, air trapped in the chamber 8 and entering the bucket as the water is forced out, will pass through the opening 18 in the upper wall of the enlargement 14 and pass 80 upwardly in the tube 13 to replace the column of water trapped in the tube by the closing of the valve. This column of water in the tube is thus permitted to fall into the lower part of the bucket and fill the chamber 85 15, water-sealing the air inlet 18, and thus trapping the air within the tube, to be carried out with the outflow of water upon the next opening of the valve. Entrapped air is, therefore, removed from the line along 90 with the water of condensation and such removal is particularly desirable in many instances.

The depending tubular member 13 thus forms an outlet passage for the water, a 95 guide for the bucket, and a support for the valve operating mechanism, and as it is positioned together with such operating mechanism, within the bucket, and therefore the casing 1 may be of minimum diameter and occupies a minimum of space. This tubular member also extends to adjacent the bottom of the bucket so that the water contained therein is drawn from adjacent the 105 bottom of the bucket and, by providing the opening 18 adjacent the lower end of this tubular member which forms the water outlet passage, entrapped air is automatically ejected from the system.

As the bucket, its guide, and the valve operating mechanism, together with the valve, are all carried by the detachable head 4, easy access to all of the movable parts of the device may be had by removing the head, 110 and by providing the detachable cap 20, easy access may be had to the valve and its seat for replacement or repair. The form of the valve 25 provides an arrangement whereby the valve may be readily detached and turned 115 end for end, giving double life when one end has become worn, and in like manner, the valve seat may be renewed by simply detaching the cap nut 22 and reversing the disk 23.

As the inlet for the steam and water of 125 condensation, is through the head 4, it is desirable that this steam and water be directed downwardly within the chamber 8 past the upper open end of the bucket, so that the 130

water will collect in the chamber 8 and be prevented by the deflecting flange 10 from entering the open end of the bucket until such time as it rises in the chamber and over-
flows into the bucket.

Obviously, changes may be made in the construction and arrangement of the parts, within the scope of the appended claims, without departing from the spirit of the invention, and I do not, therefore, limit myself to the construction or arrangement shown.

Having thus fully described my invention, what I claim is:—

- 15 1. A device of the character described comprising a casing forming a chamber for water of condensation, a valve to control the flow of water from said chamber, a tubular member depending into said chamber and forming a passage for the outflowing water, a lateral extension at the lower end of the tubular member, a bucket within the chamber surrounding the tubular member, with the tubular member extending into the bucket to near the bottom thereof, and means carried by the tubular member and operated by the bucket for operating said valve, said lateral extension having an air inlet in its upper side opened by the fall of water in the bucket upon outflow of water therefrom, through said tubular member.
- 20 2. A steam trap comprising a casing forming a water chamber, a head on said casing formed with a water outlet chamber, a valve for controlling communication between said water chambers, a tubular member depending from said head into the water chamber of the casing, a lateral extension at the lower end of the tubular member a bucket in the water chamber of the casing surrounding said tubular member and guided thereby, valve operating mechanism extending through said tubular member, said tubular member forming a water outlet passage leading to said valve, and said lateral extension provided with an air inlet in its upper side within the bucket adapted to be uncovered

by the fall of water in the bucket upon the opening of the valve.

3. A steam trap comprising a casing forming a water chamber, a head for said casing provided with a steam inlet and a water outlet, said head being also formed with an opening affording communication between said water chamber and said outlet in the head, a tubular member depending from the head in alignment with said opening and forming a water passage leading to the opening, a bucket in the water chamber into which the tubular member extends to near the bottom thereof, said tubular member being provided with a lateral enlargement at its lower end, which enlargement is open at its lower side, a valve stem extending upwardly through said tubular member to operate said valve, a lever operatively connected with said bucket in the lateral enlargement and supported within the tubular member for operating said valve stem, an arm extending from said tubular member, and a guide rod fixed to said bucket and passed slidably through said arm.

4. A steam trap comprising a casing forming a water chamber and having a head provided with a water outlet, a valve carried by the head for controlling the outlet, a tubular member depending from the head and forming a water passage leading to the valve, a bucket surrounding the tubular member which extends downward therein to near the bottom of the bucket, said tubular member being provided with a lateral extension at its lower end having an open lower side and an air inlet opening at its upper side, a valve stem for operating the valve extending downwardly through the tubular member and means operatively connected to the bucket and located within said lateral extension of the tubular member, for operating said valve stem.

In testimony whereof I affix my signature.

WILFRED H. KUHN.
